BOTTLE CLOSURE

Edgeworth Greene, Upper Montclair, N. J.

Application August 29, 1935, Serial No. 38,388

27 Claims. (Cl. 215—21)

This invention relates to improvements in cover members for bottles and the like and more particularly to improvements in assemblies made up of cover members and fastening members for securing the cover members to bottles and the like.

Heretofore it has been common practice in the art to fasten an orificed cover member, either alone or in association with valve mechanism, to a bottle by means of a metallic ferrule, part of which engages the cover member and a cylindrical part of which engages the neck of the bottle or the like. An objection has been raised to such arrangements in that a ferrule so applied to the assembly could be removed, either by distortion or destruction and used again or replaced by a similar ferrule without affording any appreciable notice that such alteration or substitution had been made.

An object of the invention is to provide an assembly of cover member and attaching ferrule so locked together that efforts to separate these parts so mutilates one or both of the parts that another similar part cannot be substituted for the mutilated part.

Another object of the invention is to provide an assembly of cover member and attaching ferrule so locked together that efforts to separate these parts result in separation of the ferrule into fragmentary portions some of which remain locked to or into the cover member so that a new similar ferrule cannot be secured to the cover member in fashion to restore the assembly to its original form.

Another object of the invention is to provide an assembly of cover member and attaching ferrule in which a part of the ferrule is locked in a suitable recess in the cover member and in which the ferrule is so selectively weakened that efforts to remove the ferrule from the recess result in separation of the ferrule into parts with part of the ferrule remaining locked in and filling the recess so that a similar complete ferrule cannot be substituted to restore the assembly to original form.

Another object of the invention is to provide a new, simple and efficient arrangement whereby an orificed cover member can be locked to the neck of a bottle or the like in such fashion that removal or substitution of any part of the assembly is effectively prevented or is rendered so apparent as to defeat such substitution.

Another object of the invention is to provide in conjunction with an orificed cover member a ferrule for engaging the neck of the bottle,

such ferrule being effectively locked to the cover member to prevent separation therefrom.

Another object of the invention is to provide a cover member having an annular recess therein for the reception of an annular portion of a ferrule member in such fashion that when the parts are secured together, separation thereof is substantially prevented.

A further object of the invention is to provide an orificed cover member having an annular undercut slot therein for the reception of an annular flange on a ferrule, such flange being forced into locking engagement with the cover member in the undercut slot.

A still further object of the invention is to provide the combination of an orificed cover member and a ferrule for attaching the cover member to a bottle or the like, such ferrule being effectively locked to the cover member which is of more frangible material than the ferrule, whereby efforts to separate the ferrule and the cover member will result in mutilation of the parts in such fashion as to be readily noticeable.

In carrying out the foregoing and other objects of the invention, a cover member for a bottle or the like is made up in such fashion as to seat directly on the top of a bottle neck and to be secured thereto in sealed relation, preferably through the medium of a washer interposed between the top of the bottle neck and the cover member. The cover member is provided with a central orifice for the discharge of liquid from the bottle. In order that this cover member can be fastened to a bottle neck, use is made of a metallic ferrule which has a skirt portion engaging formations on the bottle neck, and which has other portions engaging the cover member.

Since it is desired that removal of the cover member cannot be accomplished successfully, provision is made for so locking the ferrule to the cover member that separation of these parts cannot be expeditiously carried out. To accomplish such ends, the cover member is so constructed as to have an annular slot therein into which an annular portion of the ferrule member can be definitely and positively locked. The slot may be provided in various positions so long as such positions assure that a ferrule member once locked to the cover member cannot be removed without mutilating one or the other of the parts.

Preferably, the slot in the cover member is formed in undercut fashion so that an annular flange on the ferrule can be positioned in the slot and then forced into the undercut portion thereof to lock this flange and the ferrule against with-

drawal from the slot. In some instances, however, it will be desirable to have a slot into which a flange on the ferrule can be introduced and held therein by means of a pressed fit. In other instances, it may be desirable to provide a slot of such fashion that the ferrule can be introduced thereto, and when in proper position, cemented against withdrawal. In still further instances it may be desirable to provide the cover member with a slot extending at a suitable angle to the axis of the cover member and the ferrule, whereby when an annular flange on the ferrule is introduced into such slot, it cannot be withdrawn therefrom successfully.

15 Since the provision of an undercut slot or a slot at an angle to the axis of the cover member can be produced in a molded article, only with difficulty, and can be produced in molded articles processed with high speed automatic machinery, it has been found advisable to construct the cover member in two complementary parts which can be so shaped that when the parts are assembled, the desired slot is provided. When the cover is made of some relatively frangible material, such as porcelain, or the like, the complementary parts can be molded with high speed machinery and then permanently secured together during the firing operation by coating the contact parts of the complementary members with glazing material which serves as a cement to bind or bond the parts together when these parts are fired at relatively high temperatures in the usual manner. If the cover member is made of other materials, suitable provision can be made for locking the 35 complementary parts together.

As before mentioned, the cover member can have associated therewith suitable valve mechanism for rendering the bottle substantially non-refillable. The cover member, however, can be 40 utilized in certain instances without being associated with valve mechanism.

In the preferred embodiment of the invention, the cover member is so constructed as to have an upstanding neck portion and a body portion, 45 such body portion being provided with an undercut slot of annular formation surrounding and slightly spaced from the exterior of the neck portion. Since under ordinary conditions it is either impracticable or infeasible to provide an undercut slot in a unitary construction, the cover member is made up of two parts which are permanently joined together. By such two-piece construction it is possible to space portions of the two pieces in such fashion as to provide the desired 50 undercut slot. The cover member may be made of any suitable material, preferably, but not necessarily, of some relatively frangible material, such as porcelain or the like. It is to be understood, however, that metal or any other suitable 55 material can be used. If the cover member is made of porcelain, the two component parts thereof are assembled and subsequently united by the glazing material utilized during the firing of the porcelain.

60 The ferrule used in this invention consists of an annular skirt portion, an annular top part shaped to conform to the top part of the body of the cover member, and a depending annular flange of such dimensions as to be capable of entering the axially extending part of the undercut slot. The ferrule is locked to the cover member by moving the same downwardly relative to the cover member thereby causing the flange to enter the slot penetrating the same until the edge of 70 the flange contacts with the curved bottom of the

slot, after which further pressure causes the flange to curl outwardly in the angular or undercut part of the slot. When this flange has been forced to fit into the undercut part of the slot with the lower edge of the flange curled therein, the ferrule can be separated from the cover member only with great difficulty. In practice it has been found that in assemblies using cover members of relatively frangible material, a locked ferrule can be separated wholly from the cover member only by breaking such frangible cover member.

If desired, the flange may be so constructed that the top part thereof is provided with a number of equally spaced openings so located as to fit 15 over upstanding projections formed integrally with the cover member. These openings in the ferrule are preferably located so that they extend substantially into the perpendicular flange of the ferrule. One beneficial result from this construction resides in the fact that a tool for locking the flange into the undercut slot of a cover member can be shaped to engage the edges of the ferrule openings extending across the perpendicular flange, whereby any pressure applied to the 20 tool is transmitted vertically throughout the flange. A still further beneficial result from such construction is found in that the ferrule is somewhat weakened so that any attempt to separate the ferrule from the cover member will cause a 25 rupture of the material of the ferrule between the openings, thereby making evident any efforts to cause such separation, and leaving a portion of the ferrule embedded in the slot, filling the same, so that the flange of another ferrule cannot be introduced into this slot. Thus successful 30 substitution or replacement of ferrule is prevented. The upstanding projections on the cover member serve to aid in orienting the ferrule relative to the cover member prior to attachment, 35 and in addition, if the cover member is of relatively frangible material, any exerted effort to separate the ferrule from the cover member will cause breaking of one or more of these projections, thereby again indicating that efforts along 40 these lines have been made.

A suitable axially moving tool can be utilized for forcing the flange of the ferrule into locking engagement with the cover member. A tool especially designed for this purpose in instances 50 where the ferrule is provided with spaced openings is shown in the drawings, wherein the tool is illustrated as being formed substantially in the nature of a tubular member, the lower edge of which is scalloped so that this lower edge will 55 register with the walls of the ferrule openings at the region whereby these walls lie in the flange proper. Thus, a direct axial pressure applied onto the flange itself can be utilized for pressing the flange into the desired locking condition.

60 Other features, objects, and advantages of the invention will become apparent by reference to the following detailed description, read in the light of the accompanying drawings, wherein

Fig. 1 is a vertical section of a portion of a 65 bottle neck with a stopper embodying the present invention applied thereto.

Fig. 2 is a plan view of a ferrule made in accordance with this invention showing the manner in which the top part of the ferrule is provided 70 with spaced openings.

Fig. 3 is a partial vertical section taken substantially on the line 3—3 of Fig. 2.

Fig. 4 is a top view partially broken away of the cover member without the ferrule.

Fig. 5 is a side elevation partially in section illustrating mechanism for applying locking pressure to secure the ferrule;

Fig. 6 is a fragmentary enlarged vertical section showing the manner in which a tool engages a ferrule during the locking operation.

Fig. 7 is a section taken substantially on the line 7—7 of Fig. 5.

Fig. 8 is a fragmentary vertical section of a modification of the invention.

Fig. 9 is a similar showing of a further modification; and

Fig. 10 is a fragmentary section showing a still further modification.

Referring now to the drawings, 10 indicates generally a portion of the neck of a bottle, such bottle neck having a shoulder 11 and a flange 12 spaced therefrom below the shoulder. The stopper secured to this bottle neck is made up of a valve casing 14 having a valve seat 15 surrounding the opening 16; a flat disk-like valve member 17 made of some suitable buoyant material, a weight 18, a guard member 19, a two part cover member 20, and a ferrule 21. The valve casing 14, the valve member 17 and the weight 18 are constructed in accordance with the teaching of my copending applications Serial Nos. 8,605 and 52,300. Inasmuch as these parts have been described in detail and claimed in the said applications, further description thereof has been omitted herein. This valve casing 14 is provided with an annular flange 22 resting on top of a sealing gasket 24 which is positioned directly on the top of the bottle neck.

The cover member 20 is made up of a main portion 25 and a secondary ring portion 28. The main portion 25 has a tubular neck 27 and a body part 28, the top surface of which is stepped as shown at 29. Extending downwardly from the body part 28 are a number of spaced lugs 30 between which are arcuate shaped channels 31. The ring portion 26 has its lower surface stepped as indicated at 32 to engage the stepped upper surface of the member 25. This ring portion 26, however, does not completely engage portions of the member 25, but is so shaped as to provide a substantially annular longitudinally extending space 34 leading into a horizontal space 35. These two spaces form in effect an undercut slot extending completely around the cover member. The two parts 25 and 26 may be provided with registry means such as indicated at 36 in Fig. 5, such means serving to aid in assembling the two parts into a complete cover member, and to assure that the parts will be registered properly as will be explained later.

If the cover member is made of some frangible material, such as porcelain, etc., the two parts 25 and 26 may be permanently locked together during the firing of the device by applying a coating of glazing material between the contacting surfaces of these parts. This glazing material, when the cover member is fired, serves to bind the two component parts together as to effectively unite them into a single member. Furthermore, the guard 19 may be permanently secured directly to the lugs 30 by applying a coating of glazing material between contacting parts of these respective members, so that the guard is secured to the cover member, also during the firing thereof.

If the component parts of the cover member are made of other materials, various modes of fastening the two parts together can be used, all within the spirit of this invention.

The ferrule 21, shown in the drawings, is composed of a skirt portion 40 (Fig. 3); a top part 41 shaped to conform to the top of the ring 26, and a depending annular flange 42 of such diameter as to be capable of freely entering the space 34 in the undercut slot. In the arrangement shown, the top part 41 is provided with a number of spaced openings 44 so situated therein as to extend into the vertical flange 42. Thus the top of this flange acquires a number of arcuate shaped depressions 45 separated by narrow strips of material 46. The purpose of this construction will be explained later. With this arrangement of ferrule, the ring part 26 of the cover member is provided with a number of spaced integral upstanding projections 47 of such number and so located as to register with the openings 44 in the ferrule. The numbers of projections 47 has a definite relation to the numbers of depending lugs 30 and these parts are so relatively disposed that when the lugs are registered properly with assembling mechanism, the projections 47 will also be registered therewith.

Assuming that the cover member has been formed into a unitary structure, a ferrule 21 can be secured thereto in the following manner. The cover member is positioned uprightly upon a cylindrical support 50 with the undersurface of the cover member resting on the top of the member 50. This member 50 extends upwardly from a base 51, a distance sufficient to permit the depending lugs 30 and the guard 19 to extend down into the interior of the member 50. The inner wall of the member 50 can be provided with recesses 52 to receive portions of the outer edges of the lugs 30, thereby properly registering the cover member with this support. A number of rods 54 extend upwardly in spaced relation to the member 50, these rods 54 serving as guides to facilitate registering a ferrule in axial alignment with the cover member. As shown in Fig. 5 the space between the periphery of the cover member and the guide rods 54 is sufficient to permit the introduction of the skirt part of a ferrule. This ferrule is placed in the position shown in Fig. 5 and is locked to the cover member by an axially moving tool 60 in the form of a tube mounted on a plunger 61. The tube 60 is preferably secured to the plunger 61 by means of oppositely disposed pins 62 extending through openings 64 in the tube. These openings, as shown, are larger than the pin itself, thereby permitting some slight rotary movement of the tube relative to the flange. The lower edge of the tube 60 is scalloped as indicated at 65. These scallops are of such dimensions that the downwardly extending projections can register with the arcuate indentations 45 in a ferrule. Thus, with a ferrule in the position shown in Fig. 5, the cylinder is moved downwardly by the plunger until the scalloped edge registers with the indentations 45. The recesses 52 are so located relative to the tube 60 that the scallops on the end of the tube will be approximately properly registered with the cover member, so that when a ferrule is positioned with the openings 44 approximately aligned with the projections 47 the scallops of the tube will be in near alignment with the depressions 45 in the ferrule. Since in quantity production ferrules could not be conveniently placed manually in exact alignment with the scallops, the slight mobility of the tube relative to the plunger permits the tube to "hunt" until it is in proper register with the ferrule, after which the plunger 75

can be moved to exert a vertical driving force on the top of the flange through the agency of the tube 60.

As this vertical pressure is applied, the flange 5 is forced beyond the annular part 34 of the undercut slot. Since the inner wall of this portion is slightly inclined outwardly and curved into the horizontal part 35, and since this inner wall is glazed, in effect a die is formed so that 10 continued application of force results in the flange having its lower edge expanded into the horizontal part 35 of the slot with the ultimate result that by the time the top of the ferrule is 15 in contact with the top of ring 36 the lower edge 15 of the flange has been curled into the undercut part of the slot in the fashion shown clearly in Fig. 1.

When a ferrule has been secured to a cover member in this fashion, it is impossible, for all practical purposes, to separate the ferrule from the cover member. Should a reverse pressure be applied to the ferrule in an endeavor to straighten out the curled part of the flange, such pressure, to accomplish this result, would have to 25 be of a force sufficient to rupture the cover member, particularly if the cover member is made of some relatively frangible material and the ferrule is made of metal, as is customary. Should the force be insufficient to rupture the cover member, it would at the same time be sufficient to snap the small strips 46 between the openings 44. Should an effort be made to separate the ferrule from the cover member by means of a tool applied in any fashion near the top of the 30 assembly, the result will be a breaking of the short strips 45, and in all likelihood a break-off of one or more of the projections 47. All of the strips 45 will be ruptured without removing the curled part of the flange from the undercut slot. Since this flange fills the slot, another ferrule cannot be applied to the cover member to restore the assembly to original form. Thus each part is rendered useless for duplication purposes, and as the result, a similar assembly can 45 be provided by imitators only at the labor and expense involved in making the assembly de novo.

While the invention has been illustrated as being a construction wherein the ferrule has openings registering with projections on the cover member, it will be apparent that the openings and projections can be omitted without departing from the scope of the invention. In such a construction, the ferrule would have a solid top instead of an apertured top, and if desired this 50 solid top portion could be scored or otherwise weakened to assure separation of the ferrule into parts when efforts are made to withdraw the ferrule flange from the slot. Furthermore, the cover member just described together with the 55 flange locked thereto, can be utilized simply as a cover member for a bottle, in which instance the valve mechanism can be omitted.

In the form of the invention shown in Fig. 8, the entire cover member 70 is formed as a unitary 60 structure instead of being made up of two complementary parts. The body portion of this cover member is provided with an annular slot 71 spaced slightly from the exterior of the neck part of the cover member and extending downwardly in substantial parallelism with the axis of the neck portion. A ferrule 72 similar to the ferrule previously described in most particulars, is utilized in this embodiment of the invention. The flange 74 thereof is provided with a plurality of openings 75.

When the ferrule is to be locked to the cover member in this embodiment, a suitable quantity of cement of any desired character for the purposes of the invention can be introduced into the slot 71. The flange 74 is then pressed down into this slot causing the cement to flow in such fashion as to fill in spaces between the ferrule and the walls of the slot, and to flow into the openings 75, thereby providing a good cross bond between the walls of the slot through these openings. When this ferrule has been so locked to the cover member, it cannot be separated therefrom with any degree of satisfaction. Attempts to separate these parts will become readily apparent. This cover member as in the other embodiment 10 can be used either alone or in association with suitable valve mechanism, the cover member being illustrated as having for this purpose depending lugs 76 to which is secured a guard member 77.

In the embodiment of Fig. 9, the cover member 80 is again made of unitary construction instead of being made of complementary parts. The upper part of the body of this member is provided with a relatively wide slot 81. The exterior of the neck of the cover member is provided with a bead 82 arranged in spiral fashion extending to the bottom of the slot 81. The ferrule 84 used in this embodiment is similar in general outline to the ferrules previously described, but the upwardly extending projections on the cover member are omitted to remove any obstructions to the turning of the ferrule on the cover member threads. The ferrules are provided with a depending flange 85 substantially coaxial with the skirt part of the ferrule, such flange having its lower edge in-turned in a short flange 86 and also having its lower edge of spiral outline so that the short flange 86 can follow the thread-like rib 82. This arrangement is shown clearly by the dotted lines 87.

In assembling and locking together the cover member and ferrule of this modification of the invention, the slot 81 can be partially filled with cement and then the ferrule screwed down into this slot with the lower edge or flange 86 following the thread 82. When the flange 86 has been moved down to the bottom of the slot, if required, additional cement can be introduced into the slot so that when the cement is set the ferrule for all purposes is locked against separation from the 50 cover member. Again this cover member can be used either alone or in conjunction with valve mechanism as before described.

In the embodiment shown in Fig. 10 the cover member is again made up of two complementary parts, such parts being illustrated at 90 and 91. The part 90 has a neck portion 92 provided with an external bead 94 forming a thread. Below the neck portion 92 this cover member is of greater lateral thickness and is provided with an external bead 95 extending helically around the part to again provide a thread. The body then slopes downwardly and outwardly as at 96. The part 91 which is in the shape of a ring has a recess 97 in the inner surface thereof helically arranged to receive the helical bead 95. This ring 91 also has a downwardly and outwardly sloping surface 98 to engage the surface 96. These two parts 90 and 91 are so dimensioned that when they are assembled as shown, a space or slot 99 remains between the two parts. This slot 99 is provided for the reception of an annular flange 100 formed as an integral part of the ferrule 101.

The two parts 90 and 91 are manufactured separately and if they are made of some frangible 75

material, such as porcelain, they are separately fired. When it is desired to secure the parts together into a complete cover member and to lock the ferrule thereto, the ferrule is first slipped 5 down over the part 90 until the flange 100 rests on top of the outer shoulder of this part 90. The ring 91 is then brought into engagement with the part 90 and by properly registering the bead 95 and the recess 97, the ring can be rotated about 10 the part 90 so that it is screwed downwardly thereupon. Prior to such assembly, cement is spread upon the surface of these two complementary parts which are intended to be brought 15 into contact in the final position. This cement when set effectively locks the complementary parts together, and at the same time locks the flange of the ferrule against any appreciable successful separation. As shown in each form of the invention, the flange of the ferrule to be locked in a 20 cover member slot is of longitudinal length many times as great as its thickness or the width of the slot in which it is locked, and the slot is of corresponding depth. This ratio of parts makes 25 possible the locking of the flange in the slot in any of the manners described herein.

The cements used in any of the forms of assemblies should have the necessary tensile strength and other characteristics which adapt the assemblies to the intended uses.

30 I claim:

1. A combination of the character described comprising an orificed cover member for the neck of a bottle or the like, said cover member being provided with an annular slot, and a ferrule for 35 securing said cover member to the neck of a bottle or the like, said ferrule having a skirt portion to fit around the bottle neck and having an annular flange portion locked in said annular slot and having a weakened portion between said 40 skirt and said flange whereby the ferrule is substantially locked against separation from the cover member independently of the bottle, and attempted removal of same will rupture the weakened portion of the ferrule.

45 2. A combination of the character described, comprising an orificed cover member for the neck of a bottle or the like, said cover member being provided with an annular slot substantially coaxial with the orifice therein, and a metallic ferrule having a skirt portion and having an annular flange portion locked in said slot and having a 50 weakened portion between said skirt and said flange for preventing separation of the cover member and the ferrule without rupturing said 55 weakened portion.

3. A combination of the character described comprising an orificed cover member for the neck of a bottle or the like, said cover member being provided with an annular slot having an offset 60 part, and a metallic ferrule having a skirt portion to fit around the neck of a bottle and having a flange portion fitting in said slot with part of said flange portion spread into the offset part of the slot.

65 4. A combination of the character described comprising an orificed cover member for the neck of a bottle or the like, said cover member being provided with an annular undercut slot, and a metallic ferrule having a skirt portion to fit around the neck of a bottle and having a flange 70 portion fitting in said undercut slot with the edge of said flange portion spread into the undercut part of the slot.

5. A combination of the character described 75 comprising an orificed cover member for the neck

of a bottle or the like, said cover member having an annular slot therein, part of which is substantially coaxial with the orifice therein, and part of which extends laterally from the bottom of the first named part, and a metallic ferrule 5 having a skirt portion to fit around the neck of a bottle and having a flange portion coaxial with the skirt portion to fit in said slot, the lower edge of said flange portion being curled into said laterally extending part of the slot to substantially 10 prevent separation of the ferrule from the cover member.

6. A combination of the character described comprising an orificed cover member for the neck of a bottle or the like, said cover member having an annular slot therein, part of which is substantially coaxial with the orifice therein, and part of which extends laterally from the bottom of the first named part, and a metallic ferrule 15 having a skirt portion to fit around the neck of a bottle and having a flange portion coaxial with the skirt portion to fit in said slot, the lower edge of said flange portion being curled into said laterally extending part of the slot to substantially 20 prevent separation of the ferrule from the cover member, said cover member being weakened intermediate the skirt part and the flange part.

7. A combination of the character described comprising an orificed cover member for the neck of a bottle or the like, said cover member being 30 provided with an annular undercut slot, and a metallic ferrule having a skirt portion to fit around the neck of a bottle and having a flange portion fitting in said undercut slot with the edge of said flange portion spread into the undercut 35 part of the slot, said cover member having spaced raised projections surrounding the orifice, said ferrule being provided with spaced openings to register with said raised projections.

8. A combination of the character described comprising an orifice cover member for the neck of a bottle or the like, said cover member having an annular slot therein, part of which is substantially coaxial with the orifice therein, and part of which extends laterally from the bottom of the first named part, and a metallic ferrule 40 having a skirt portion to fit around the neck of a bottle and having a flange portion coaxial with the skirt portion to fit in said slot, the lower edge of said flange portion being curled into said laterally extending part of the slot to substantially 45 prevent separation of the ferrule from the cover member, said cover member having spaced raised projections surrounding the orifice, said ferrule being provided with spaced openings to register with said raised projections.

9. A combination of the character described comprising an orificed cover member for the neck of a bottle or the like made up of complementary parts secured together, said parts being shaped to provide an annular slot between portions of adjacent surfaces thereof, and a metallic ferrule having a skirt portion to fit around a neck of a bottle and having a flanged portion 50 locked in said slot.

10. A combination of the character described comprising an orificed cover member for the neck of a bottle or the like, made up of complementary parts secured together, said parts being shaped to provide an annular undercut slot between portions of adjacent surfaces thereof, and a metallic ferrule having a skirt portion to fit around the neck of a bottle and having a flange 55 portion locked in said annular skirt with the 60

edge of the flange curled into the undercut part of the slot.

11. A combination of the character described comprising an orificed cover member for the neck of a bottle or the like, made up of complementary parts secured together, said parts being shaped to provide an annular undercut slot between portions of adjacent surfaces thereof, and a metallic ferrule having a skirt portion to fit around the neck of a bottle and having a flange portion locked in said annular slot with the edge of the flange curled into the undercut part of the slot, said ferrule being provided with a plurality of spaced openings intermediate the skirt and flange portions, said cover member having spaced raised projections extending through the openings in said ferrule.

12. A combination of the character described comprising an orificed cover member for the neck of a bottle or the like, said cover member being made up of complementary parts secured together, said parts being shaped to provide between portions of adjacent surfaces thereof a slot partially coaxial with the cover member orifice and partially undercut in a lateral direction, and a metallic ferrule having a skirt portion to fit around the neck of a bottle and having a flange portion coaxial with the skirt portion, said flange portion being locked to the cover member by introduction of the lower edge thereof into the undercut part of the slot.

13. A combination of the character described comprising an orificed cover member for the neck of a bottle or the like made up of complementary parts secured together, said parts being shaped to provide an annular slot extending inwardly from the periphery of the cover member and a metallic ferrule having a skirt portion to fit around the neck of a bottle and having an angular flange portion locked in said slot.

14. A combination of the character described comprising an orificed cover member for the neck of a bottle or the like, said cover member having a neck portion defining the orifice and being provided with an annular slot surrounding the neck portion and a metallic ferrule having a skirt portion to fit around the neck of a bottle and having a flange portion to fit in said slot, said flange portion being locked in said slot by means of cement or the like.

15. A combination of the character described comprising an orificed cover member for the neck of a bottle or the like, said cover member having a neck portion defining the orifice and being provided with an annular slot surrounding the neck portion and a metallic ferrule having a skirt portion to fit around the neck of a bottle and having a flange portion to fit in said slot, said flange portion being locked in said slot by means of cement or the like, said flange portion being provided with a plurality of openings for the passage of cement whereby the cement can be cross bonded to the walls of the slot.

16. A combination of the character described comprising an orificed cover member for the neck of a bottle or the like, said cover member having a neck portion and being provided with an annular slot surrounding said neck portion, said neck portion having external threads extending into said slot, and a metallic ferrule having a skirt portion to fit around the neck of a bottle and having a flange portion to fit in said slot, said flange portion having a thread formation to engage the threads on said neck part of

the cover member and cement locking said flange portion of the ferrule in said slot.

17. A device of the character described comprising an orificed cover member for the neck of a bottle or the like, said cover member having an annular slot therein, part of which is substantially coaxial with the orifice therein, and part of which extends laterally from the bottom of the first named part.

18. A device of the character described comprising an orificed cover member for the neck of a bottle or the like, said cover member having an annular slot therein, part of which is substantially coaxial with the orifice therein, and part of which extends laterally from the bottom of the first named part, said cover member having spaced raised projections surrounding the orifice.

19. A device of the character described comprising an orificed cover member for the neck of a bottle or the like made up of complementary parts secured together, said parts being shaped to provide an annular slot between portions of adjacent surfaces thereof with portions of said slot extending in different planes.

20. A device of the character described comprising an orificed cover member for the neck of a bottle or the like, said cover member being made up of complementary parts secured together, said parts being shaped to provide between portions of adjacent surfaces thereof a slot partially coaxial with the cover member orifice and partially undercut in a lateral direction.

21. A device of the character described comprising an orificed cover member for the neck of a bottle or the like, said cover member having a neck portion and being provided with an annular slot surrounding said neck portion, said neck portion having external threads extending into said slot.

22. A device of the character described comprising a metallic ferrule for locking a cover member to a bottle, said ferrule having a skirt portion to fit around the neck of a bottle and having a flange portion coaxial with the skirt portion to permanently fit in a slot in the cover member, said flange having a length many times as great as its thickness and as the width of the slot, said slot being of corresponding depth, said ferrule being weakened intermediate the skirt and flange portions to rupture and separate the flange portion from the skirt portion.

23. A device of the character described comprising a metallic ferrule for locking a cover member to a bottle, said ferrule having a skirt portion to fit around the neck of a bottle and having a flange portion to permanently fit in an annular slot in the cover member, said flange having a length many times as great as its thickness and as the width of the slot, said slot being of corresponding depth, said ferrule being provided with a plurality of spaced openings intermediate the skirt and flange portions to rupture and separate the flange portion from the skirt portion.

24. A device of the character described comprising a metallic ferrule for locking a cover member to a bottle, said ferrule having a skirt portion to fit around the neck of a bottle and having a flange portion to fit in a slot in the cover member, said flange portion having a thread formation to engage threads on said neck part of the cover member.

25. The method of locking a ferrule, having a skirt portion and a spaced tubular flange portion, to a cover member having an undercut slot

5 therein which comprises introducing said tubular flange portion of the ferrule into said slot, applying pressure to the top of the tubular flange portion in such fashion that lines of pressure coincide with the lines of the tubular flange portion and continuing said application of pressure until the lower edge of the tubular flange portion is expanded into and curled in the undercut part of said slot.

10 26. The method of locking a ferrule, having a skirt portion and a tubular flange portion the top of which is provided with a series of arcuate shaped indentations, to a cover member having an annular undercut slot therein which comprises introducing the tubular flange portion of the ferrule into the slot and applying pressure by an axial moving tool to the top of the tubular flange portion along the indentations thereof to

force the lower edge of said tubular flange portion into the undercut part of the slot until such lower edge of the tubular flange portion is curled in the undercut part of the slot.

15 27. The method of locking a ferrule, having a skirt portion and a tubular flange portion the top of which is provided with a series of indentations, to a cover member having an annular undercut slot therein which comprises introducing the tubular flange portion of the ferrule into the slot and applying pressure by an axial moving tool to the top of the tubular flange portion along the indentations thereof to force the lower edge of said tubular flange portion into the undercut part of the slot until such lower edge of the tubular flange portion is turned into the undercut part of the slot.

EDGEWORTH GREENE.
